UNITED STATES PATENT OFFICE.

JOHN THOMAS SIMPSON, OF NEWARK, NEW JERSEY.

REINFORCED-CONCRETE BUILDING.

1,392,532.

Specification of Letters Patent.

Patented Oct. 4, 1921.

Application filed April 23, 1919. Serial No. 292,211.

To all whom it may concern:

Be it known that I, JOHN T. SIMPSON, a citizen of the United States, and a resident of Newark, county of Essex, and State of New Jersey, have invented a certain new and useful Reinforced-Concrete Building, of which the following is a specification.

The invention relates to reinforced concrete structures and more particularly that class of such structure wherein pre-cast or shop molded members and field cast members are employed.

In such structures the field made elements enter largely into the construction and such field work is generally carried out under the worst possible conditions. The work must be done in the open and is often delayed, and much material lost by adverse weather conditions. The molds employed in casting the field made elements must necessarily be of the most flimsy and temporary character.

The object of my invention is to provide a building in which all of the framework, such as studs, floor beams, floor slabs, ceiling slabs, outside and inside wall slabs, roof slabs, and cornices are pre-cast of standardized sections which may be carefully made by means of proper machinery, and suitably finished and cured in a factory where working conditions are at the best, and which may be kept in stock and delivered to the building site when desired.

A further object is the production of a building formed principally of pre-cast elements and which is adaptable to any type of construction from a small shed garage to a skyscraper, in which the exterior surface may be of any material from wood to granite or steel, and the interior walls, ceiling and floors may be of any desired material or finish.

A further object is the production of a moisture-proof block or slab of reinforced concrete for interior or exterior wall members.

A still further object is the production of an improved method of securing wooden sleepers to pre-cast reinforced concrete elements such as floor slabs.

These and further objects will more fully appear in the following specification and accompanying drawings considered together or separately.

One embodiment of the invention is illustrated in the accompanying drawings in which like parts in all of the several figures

are designated by corresponding reference characters and in which—

Figure 1 is a fragmentary sectional view of a building embodying the invention. 60

Fig. 2 is a detail sectional view of a wall at a floor line.

Fig. 3 is a similar view at another floor line.

Fig. 4 is a horizontal section taken on the line 4—4 of Fig. 1. 65

Fig. 5 is a detail sectional view of the junction of a floor beam and a partition stud.

Fig. 6 is a horizontal section of a partition stud. 70

Fig. 7 is a detail section on the line 7—7 of Fig. 1.

Fig. 8 is a section on the line 8—8 of Fig. 1.

Fig. 9 is a section on the line 9—9 of Fig. 1. 75

Fig. 10 is a detail section of a gable.

Fig. 11 is a detail section of a window.

Fig. 11^a is a section on the line a—a of Fig. 11. 80

Fig. 12 is a detail section similar to Fig. 7 but showing a modified form of ceiling slab.

Fig. 13 is a section on the line 13—13 of Fig. 7.

Fig. 14 is a section on the line 14—14 of Fig. 12. 85

Fig. 15 is a detail sectional view, on a much enlarged scale, of the preferred form of wall and roof slab.

Fig. 16 is a detail sectional view illustrating the process of making the said slab. 90

Fig. 17 is a detail section of the ridge pole.

Fig. 18 is a detail sectional view illustrating a method of securing floor or roof sleepers in position, and Fig. 19 is a detail section of a joint. 95

In carrying out the invention a field cast reinforced concrete footing 1 is laid defining the outside walls of the structure to be erected, and field cast footings are positioned at points where partition studs are to be erected. At each point where a stud is to be erected a pin 2 projects from the footing. The footing may form the floor of the cellar.

A pre-cast stud 3 having a cavity 4 filled with soft concrete is positioned over each pin and the projecting portion of the latter is embedded in the recess 4. The opposite end of the stud is provided with a recess 4^a which is filled with concrete in which a portion of a pin 5 is embedded. 105

A pre-cast floor beam 6 is positioned with

its end resting on the top of the stud 3. The opposite end of the floor beam may rest on a stud at the opposite side of the building or it may and preferably does rest on the top 5 of a partition stud 7. The reinforcements of the studs project from the ends thereof. The reinforcements of the floor beams project over the tops of the studs.

A mold is erected around the periphery of 10 the building and incloses the tops of the studs and the ends of the beams. Reinforcements are positioned in the mold. Concrete is run into the mold embedding the reinforcing members. This forms a field cast girt 8 which extends around the entire building 15 and embeds the ends of all of the studs and beams at that level. Before the concrete sets a pin 9 is forced into it and a portion of the pin projects above the concrete.

20 The top of the partition studs 7 may be joined to each other and to the wall studs in line therewith by field cast beams 8^a.

A stud similar in all respects to the stud 3 is now positioned in the same manner over 25 each stud 3 and the above described operation is repeated until the ultimate height of the structure is reached.

The studs are cast with a recess 11 in opposite sides thereof producing an H-shaped 30 cross section. The reinforcements 12 project into the recesses and during the manufacture are bent against the wall of the recess. When the studs are erected the members 12 are bent outward to project into the 35 recess.

The floor beam has a foot 13 at its lower edge and head 14 at its upper edge. A groove 15 is cast in the upper edge and the reinforcements 16 are treated in the same 40 manner as those of the studs.

At the top of the top row of studs, a girt 17 is formed. The upper edge of the girt 17 is given an incline corresponding to that of the roof and a portion 18 of one side of the 45 girt is inclined at a right angle to the top. A pin 19 projects from the top of the girt and enters a recess in a roof rafter 20. The rafter has a shoulder 21 which abuts against the part 18. The rafter projects beyond the 50 stud to form the eaves.

In a hip roof construction a mold is built along the center line of the building. Reinforcements 20^a are laid in the mold. The projecting reinforcements of the rafters are 55 hooked over the rods 20^a and a field cast ridge pole 20^b is cast in the mold and embedding the reinforcements.

The top of the rafter is formed like the top of the floor beams. Roofing slabs 22 of 60 reinforced concrete are placed over the rafters. The edges of the slabs reach to the edges of the recess 23. The projecting ends of the slab reinforcements project into the recesses which are grouted to the level of the 65 tops of the slabs.

During the manufacture of the roof slabs U-shaped wires 24 are embedded in them with the ends of the wire projecting from the face of the slab. Sleepers 25 are laid upon the slabs and the ends of the wires are 70 bent over them and twisted. Roofing 26 such as tiling or shingles is secured to the sleepers in any desired manner.

Starting at the footing 1 outside slabs 26^a are placed against the studs in belts around 75 the entire building. The top and one side of each slab is provided with a ridge 27 and the bottom and opposite side has a correspondingly shaped groove 28. The side ridge of one slab will fit into the groove of 80 the adjoining slab. The reinforcements of the slabs project from the side edges thereof and are bent into the grooves 11 in the studs. Grouting 29 is run into the grooves 11 to embed the projecting reinforcements of the 85 stud and slabs.

A second belt of slabs is placed upon the first belt with the ridges of one belt resting in the grooves. This is continued from the footing to the under side of the cornice 30. 90 The outside joints of the wall slabs 26^a are tight and no exterior covering is required, but such joints may be pointed up if desired.

The floor slabs 31 are secured in position in the same manner as are the roof slabs 22, 95 as are the floor sleepers 32 and flooring 33 when employed.

The inside wall slabs 34 and partition slabs 35 are secured to the studs in the same manner as are the outside slabs 26. The 100 tongue and groove joint may be employed or it may be omitted as desired.

The ceiling slabs 36 of reinforced concrete are provided with flanges 37 which engage the feet 13 of the floor beams. The 105 bodies of the slabs 36 are flush with the lower ends of the beams and a flush ceiling is produced. One side edge of each ceiling slab is provided with a flange 38 which rests upon the edge of the adjoining slab. The 110 joints between the slabs 36 may be pointed up or not.

When a timbered effect is desired the flanges 37 may be omitted and the ends of the slabs 36 will rest upon the top of the 115 foot 13. The flanges 38 will be placed below instead of on top of the slab.

Where the roof projects beyond a gable wall to form a cornice a projecting rafter 39 is set before the girt 17 is cast. The 120 rafter 39 will support the gable end and will carry soffit closing slabs 40 in the same manner as the eaves ceiling slabs 41 are supported.

The lowermost row of slabs 34 at the 125 floor line may have flanges 42 against which the flooring slabs will abut. This will form an air and moisture check and will close the space between walls against vermin and acts as a fire stop. The said slabs may also be 130

provided with an enlargement 43 to form a foot board around the room.

When the wall slabs 26^a and 34 are placed in position spaces are left for the doors and windows. The studs 3 are preferably spaced apart a distance sufficient for this purpose. Where each window is to come the studs on opposite sides of the space are provided with projections 44 on which the window sill 10 slabs 45 of reinforced concrete rest. For convenience in manufacture all of the studs 3 are provided with projections 44. The sills 45 project over the wall slab 26^a at the lower edge of the window opening and a 15 flange 46 extends down on the outer face of the slab. At the top and sides of the window opening the wall slabs 26^a are provided with inturned flanges 47. The window door frame 49 as the case may be, is placed in the 20 opening and is retained in position by the slabs.

In casting either the inside or outside wall slabs, roof slabs, and window and door sills, waterproof building paper 48 is first 25 laid in the bottom of the mold, the reinforcements are placed in position, and the mold is filled with concrete. When the cement dries the paper will adhere to the surface of the slab. When the slab is placed in position 30 the paper will come next to the stud, beam or rafter to which the slab is secured, thus preventing frost and moisture from penetrating the wall construction. The building will be water and frost proof with 35 out an additional erecting operation.

Instead of placing the paper 48 in the mold first, the mold may be partially filled with concrete, the papers may now be laid in place and the mold filled with concrete. 40 Due to the cross sectional shape of the studs, with the exception of the projecting reinforcements into the groove 11 from both the stud and slabs, the stud itself is increased in strength in the same manner as 45 when a flat plate is riveted to an H-shaped steel column, thus increasing the strength and bringing into play, as a structural member, the slab that forms the wall. This is also true of the floor beams and roof rafters.

50 In the two latter cases, however, the bringing into play of a portion of the floor or roof, as the case may be, gives a T section thus materially increasing the strength in the upper or compression portion of the beam. This is of great advantage as it permits the use of much lighter sections for 55 economical transportation and ease in handling. The grouting in the groove in the top of the beam and between the edges of the 60 slabs raises the strength of the beam to that desired.

It is to be understood that the outer surface of the building may be plastered or stuccoed and the walls and ceilings be plastered if desired.

Instead of flooring the upper surface of the floor slabs may be roughened and a plastic material laid over them to form the floor. The roof may be finished in the same manner. This construction is particularly applicable to small buildings such as garages. 70

In some situations the groove 11 on one side of the stud may be omitted where a single wall structure is desired in buildings of the shed or garage type. 75

Instead of using concrete slabs for the outer wall, brick or stone veneering may be employed as in steel frame construction. Horizontal sleepers may be set into the studs in the same manner as are the floor 80 or roof sleepers and shingles may be nailed to the sleepers. The sleepers may be placed in vertical position secured to the field cast girts and wide wooden clap boards nailed in place, the roof may be covered with 85 shingles giving the effect of a frame building. Such a building will be a strictly fire-proof structure with the exception of the outside jacket.

The building may be of any height, the 90 studs being proportioned to the load to be carried. The corner studs and such others as are considered necessary or desirable may be provided with knees or brackets which will be united with the field cast girts for 95 wind bracing.

In accordance with the provisions of the patent statutes I have described the principle of my invention, together with the structure which I now consider to represent 100 the best embodiment thereof, but I desire to have it understood that the structure shown is merely illustrative, and that the invention may be carried out in other ways.

Having now described my invention what 105 I claim and desire to secure by Letters Patent is:

1. A building comprising pre-cast reinforced concrete studs and floor beams there being recesses in the studs, a field cast reinforced concrete girt engaging the extremities of the studs and beams, said girt extending entirely around the building, pre-cast, reinforced wall slabs secured to the surfaces of and forming part of the studs, reinforcements projecting into and grouted in 110 the recesses whereby such slabs will act as flanges to increase the strength of the studs. 115

2. A building comprising pre-cast reinforced concrete studs in axial alignment and 120 floor beams, there being longitudinal recesses in the studs, a field cast reinforced concrete girt engaging the extremities of the studs and beams, said girt extending entirely around the building, pre-cast, reinforced wall slabs on each side of said studs secured to the surfaces of and forming part of the 125 studs, reinforcements projecting at right angles from the slabs into the recesses, grouting filling the recesses and embedding the 130

projecting reinforcements whereby such slabs will become integral parts of the studs and form flanges to increase the strength of the studs.

- 5 3. A building comprising pre-cast studs, beams, rafters, wall slabs, floor slabs, ceiling slabs and roof slabs of reinforced concrete, said beams having projecting reinforcements, a field cast girt embracing the 10 ends of the studs and beams and the projecting reinforcements of the latter, a field cast girt embracing the ends of studs and carrying rafters, reinforcements projecting from the rafter into the girt, and a lateral 15 shoulder on the rafter, said shoulder abutting against the girt.
4. A building comprising pre-cast studs, beams, rafters, wall slabs, floor slabs, ceiling slabs and roof slabs of reinforced concrete, said beams having projecting reinforcements, a field cast girt embracing the 20 ends of the studs and beams and the projecting reinforcements of the latter, a field cast girt embracing the ends of the studs and carrying rafters, reinforcements projecting 25 from the rafter into the girt, a lateral shoulder on the rafter, said shoulder abutting

against the girt, roof slabs carried by the rafter, reinforcements carried by the roof slabs and projecting from the face thereof, 30 sleepers carried on the roof slabs, the projecting reinforcements engaging the sleepers, and a roofing carried by the sleepers.

5. A building comprising pre-cast reinforced concrete studs and floor beams, a field 35 cast reinforced concrete girt engaging the extremities of the studs and beams, said girt extending entirely around the building, pre-cast floor slabs supported on the beams, U-shaped elements embedded in the slabs, the 40 legs of such elements projecting from the slabs, there being a groove in the slab between the legs, a sleeper resting in the groove, the legs of the element embracing the sleeper and being secured together to 45 retain the latter in position, and flooring secured to the sleepers.

This specification signed and witnessed this fourth day of April, 1919.

JOHN THOMAS SIMPSON.
